By
James Stearns,
ATTORNEY.

UNITED STATES PATENT OFFICE.

FRANCESCO RENZO, OF PATERSON, NEW JERSEY.

SHUTTLE TENSION.

1,228,479.

Specification of Letters Patent.

Patented June 5, 1917.

Application filed September 22, 1916. Serial No. 121,603.

To all whom it may concern:

Be it known that I, FRANCESCO RENZO, a subject of the King of Italy, residing at Paterson, in the county of Passaic and State 5 of New Jersey, have invented certain new and useful Improvements in Shuttle Tensions, of which the following is a specification.

This invention relates to that class of tension means for shuttles in which a spring actuated lever member having a series of eyelets coact with a series of stationary eyelets to exert the required tension, and its object is to provide a tension device which 10 shall be inexpensive to manufacture and simple in construction and in which the eyelets are mounted in a novel way to permit their being readily replaced, when damaged or worn, or adjusted to different distances 15 from each other.

In the accompanying drawing,

Figure 1 is a side elevation, partly in section, of a shuttle equipped with my improved tension device;

Fig. 2 shows the blank from which the body member of the device is made, after the first operation has been performed thereon;

Fig. 3 is a plan view of said body member;

Fig. 4 are elevations of one of the eyelet members;

Fig. 5 is a side elevation, partly in section, and Figs. 6 and 7 end elevations of the 35 device; and,

Figs. 8 and 9 are a side elevation, partly in section, and an end elevation of a modified form of the device.

Referring, first, to Figs. 1 to 7, to form 40 the body member of the device I take a suitable strip *a* of sheet metal and bend back its longitudinal edges so that for a little more than half the length of the strip said edges will form opposite grooves *b* (Fig. 7) and for the remainder of the length of the strip said edges will form flat folds *c*.

Thereupon, upon a transverse axis parallel with the material of the strip *a*, I bend the end portion of the strip which has its edges *c* flat-folded into an underlying loop *d*, leaving the extremity *e* of said end portion projecting downwardly. The loop *d* forms the bearing portion of the device, being adapted to receive the fulcrum pin *f* (Fig. 1) while the extremity *e* affords a projection to which to attach the usual rubber

band or other spring *g* for holding the device normally retracted; for the attaching of spring *g* the extremity *e* may be provided with the aperture *h*.

Each eyelet member consists of an eye *i* and a block-shaped base *j* formed dovetailed in cross-section so as to fit the channel afforded by the grooves *b* of the body member. The eyelet members are arranged 60 in a row, preferably abutting each other in said channel, and may be removably secured therein by shellac or other cement *k*, or otherwise. The eyes *i* each afford a straight thread contact surface *i'* at the 65 top, allowing the thread to shift, thus to prevent wearing a nick in the eye.

Referring to Figs. 8 and 9, the body member *l* is a suitable length of wire, preferably square in cross-section, being straight for 70 the major portion thereof but having one end formed into a loop *m* and the extremity *n* thereof projecting downwardly. The loop *m* forms a bearing portion to receive the fulcrum pin *f* and the extremity *n* is 75 adapted for the attachment thereto of the spring *g*.

Each eyelet member in this case includes an eye *o* and a base *p*, the latter being formed with a cross-sectionally rectangular 80 bore *q*, so as to permit the eyelet members being threaded onto the straight portion of the body member *l*, as shown in Fig. 8. Shellac or other cement *r* may be used to hold the eyelet members removably on the 85 body members *l*.

In either construction, the eyelet members are adapted to coöperate as thread guides with the fixed thread guides *s* of the shuttle, as shown in Fig. 1, the weft thread 90 or filling extending in zig zag fashion with respect to the two sets of guides in the usual way.

The eyelets may in either case be made of porcelain or other vitreous material or 100 the like. Their bases being block-shaped insure the eyelets being held rigidly and in a manner to withstand handling without distortion or dislocation.

Having thus fully described my invention, what I claim as new and desire to secure by Letters Patent is:—

1. A tension device for a shuttle tension means of the class described including an elongated body member and a series of eyelet members each including an eyelet proper and a block-shaped base, the several bases

being removably secured in a row on said body member.

2. A tension device for a shuttle tension means of the class described including an elongated body member formed of an elongated piece of sheet material having its longitudinal edges bent back and forming opposite grooves for a part of the length of the piece and a series of eyelet members arranged on the body member and engaged in 10 said grooves and thereby held to the body member.

3. A tension device for a shuttle tension

means of the class described including an elongated body member formed of an elongated piece of sheet material having its longitudinal edges bent back and forming opposite grooves for a part of the length of the piece and a series of eyelet members arranged on the body member and engaged in 20 said grooves and thereby held to the body member, one end of said piece being bent into a loop-including bearing-forming projection.

In testimony whereof I affix my signature. 25.

FRANCESCO RENZO.
